CONTINUOUS GRATING STRUCTURE

Original Filed June 21, 1928

FIG. 1.

UNITED STATES PATENT OFFICE

PAUL LEON PRICE, OF MOUNT VERNON, NEW YORK, ASSIGNOR TO IRVING IRON WORKS COMPANY, A CORPORATION OF NEW YORK

CONTINUOUS GRATING STRUCTURE

Application filed June 21, 1928, Serial No. 287,292. Renewed September 6, 1929.

This invention relates to metal structures which may serve as ventilated floorings, runways and similar structures, and also as metal reinforcements for all kinds of concrete structures. It consists essentially of a simple form of interlocking joint by which standardized panel units of grating, each comprising a plurality of straight bars and intervening bent strips connecting and spacing apart said bars, may be conveniently and easily bolted, pinned or spot-welded together on the job so as to produce a built-up structure of indefinite length and of substantially uniform mesh throughout, the joints in which structure shall present nearly the same resistance to both longitudinal and bending stresses as do the main bodies of the component panels themselves.

In substance it presents another embodiment of the general idea described and more broadly claimed in my copending application Serial No. 287,291, filed of even date herewith, and is distinguished from the specific embodiment thereof illustrated in said copending application in that the present invention is more easily applicable to gratings in which the straight bars and bent strips are all of the same depth.

The best form of apparatus at present known to me embodying my invention is illustrated in the accompanying sheet of drawings in which

Fig. 1 is a plan view of the interlocking, abutting ends of two panels of grating connected together to form a joint in accordance with my present invention, the outer ends of each panel being broken away.

Fig. 2 is a cross section on line 2—2 of Fig. 1, and

Fig. 3 is a perspective detail view of the ends of two straight bars and two bent strips in the relative position they would occupy in forming a joint, but separated laterally for clearness.

Throughout the drawings like reference characters indicate like parts. 1, 3, 5 and 7 represent portions of the parallel straight bars in the right hand panel. 2, 4 and 6 represent intervening bent strips fastened to the

straight bars by rivets 8, 8, or other means in the usual way. Similarly, 11, 13, 15, and 17 represent portions of the straight bars in the lefthand panel of grating and 12, 14, and 16 portions of the intervening bent strips which, together with the straight bars, form such lefthand panel. Preferably the left hand ends of the straight bars of each panel, as indicated at 1^a, 3^a, 5^a and 7^a, are laterally offset at 1^c, 3^c, 5^c and 7^c, a distance substantially equal to the thickness of the main body of the bar, and which offset portions are of a length slightly greater than the length of a single mesh of the grating. The said offset portions of the straight bars (with the exception of the outer bar 1 of each panel which would form the outer edge of an entire floor or runway) have notches such as 5^b and 7^b (see Figs. 2 and 3) cut preferably in their lower edges of a size and shape to receive the hook around the partly cut away end portions, as 12^b, 14^b of the bent strips of the next panel to the left, as shown in Figs. 2 and 3.

As indicated in Fig. 3, in forming each element joint an offset portion, as 3^a of bar 3, overlaps the end of a straight bar, as 13, and the end of a bent strip, as 2^a, of one panel overlaps the cutaway end, as 12^b, of a bent strip of the next panel, all being pinned together by one of the split pins 10, which passes through holes 10^x, 10^y and 10^z, punched respectively in 2^a, 12^b and 13, and in other corresponding elements. Such a pin is shown in cross section in Fig. 2, where a corresponding end 14^b of a bent strip is shown nested in a notch 5^b in extension 5^a of a straight bar 5.

The straight bars are all of the same length, but the consecutive bars are staggered longitudinally with reference one to another by a distance substantially equal to half of the grating mesh. The bent strips are also all of equal length, such length, however, being less than the length of the straight bars by a distance equal approximately to the length of a grating mesh. Each bent strip on one side of an adjacent straight bar is so located with reference to that straight bar that said straight bar projects beyond each end of said bent strip by a distance approximately equal to one

half a grating mesh. Thus in Fig. 1, the straight bar 15 is shown projecting beyond the corresponding end of the bent strip 14 by one-half a mesh length and the straight bar 5 portion, marked 5, which would be a continuation of the part marked 15 in any unit panel, projects one half a mesh length beyond the left hand end of the bent strip portion 4, which in any panel unit would be a continuation of the part marked 14. Similarly each straight bar, as 5-15, has its lefthand end in the same transverse line as the lefthand end of the bent strip 6-16 which is on its other side, while its right hand end projects, as shown in Fig. 1, a distance of a whole mesh length beyond the right hand end of the bent strip 6-16.

Also all the bent strips, as 2-12, 4-14, of each unit panel are staggered longitudinally a distance of one half mesh with reference one to another.

Those portions 1^a, 3^a, 5^a, 11^a, 13^a, &c., which project beyond the ends of the bent strips, and the ends 2^a, 4^a, 14^a, &c. of all the bent strips, 25 are all left free from fastening means when the panel is manufactured in the shop, but have registering holes 9^a, 10^a, 10^b or 10^c punched through them at standard rivet positions, as indicated in Fig. 3.

30 Preferably the right hand end of each bent strip is so cut away as to make the remaining projecting section (as 12^b or 14^b, see Figs. 2 and 3) of a width equal to one half the uniform depths of all bars and strips, and the 35 notches (as 3^b) in the straight bar offset portions are of similar half depth to receive said projecting sections.

To increase the resistance of the joint to transverse bending strains, the overlapping 40 portions of the straight bars, as 1^a, 11^a, 3^a, 13^a, &c. will be bolted or pinned together at 9, 9, as shown in Fig. 1. The end portions of all straight bars having been punched in the shop, as indicated at 9^a in Fig. 3, can receive such 45 fastening means 9, when they are overlapped to form a joint, shown in Fig. 1.

It is evident that the joint between any two abutting panels of grating thus formed will present nearly as great a resistance to longitudinal strains tending to pull them apart, as do the main bodies of the panels themselves, that the straight bars of any two panels being joined together by the long splices at 9, 9, and said splices being staggered in consecutive 55 lines of straight bars, the resistance of the joint to transverse bending strains will be very great, and that the line of continuous grating formed by the joining together of a series of panels in this manner will present a substantially uniform mesh throughout. The 60 resistance to longitudinally exerted stresses is rendered particularly effective by the interlocking action of the notches 3^a, 5^b, &c. in the 65 straight bars hooking around the joints be-

tween the surrounding other portions of the grating which are held together by fastening means 10.

It is evident, also, that various changes could be made in the details of the structure illustrated and above described without departing from the underlying principles of the invention above set out generically. Other forms of grating mesh could be substituted, the extent of overlap between straight bars or between bent strips or both, might be varied from that shown in the drawings. The desired overlapping of the ends of the straight bars might be attained without the specific short bent offset such as is shown at 1^c, 3^c, &c. 75 and other minor details of conformation of the elements, or location of fastening means, made as might be desirable in any particular case.

It is equally evident that by the use of 85 my invention an unlimited number of reasonably short standard panel units of grating such as would be presented by joining together the broken away ends of the panel sections shown in Figs. 1 and 2, can be cheaply 90 manufactured by quantity production in the shop and then, after transportation to the place of use, can be quickly fastened together without the use of means other than simple bolts or cotter pins or spotwelding apparatus 95 to form continuous floorings or other structures which will present substantially all the advantages which might result from the building of such continuous floorings, &c. by 100 uniting on the job bars and strips of very 105 great length. It will be understood that in building up floorings of any considerable width, the constituent strips of flooring structure formed by the use of my invention 110 may be united side by side with the joints in said respective strips staggered with reference one to another, the general arrangements of these joints and fastenings being similar to those fully described in Patent No. 1,609,134, granted May 17, 1927, upon an application of W. A. Van Hoffen. 110

Having described my invention, I claim:

1. In a continuous grating structure the combination of a series of panels of grating clamped together end to end, each panel comprising a plurality of straight bars of uniform depth held together, but spaced apart, by intervening bent strips of an equal uniform depth fastened to them at spaced apart points, certain of the extremities of the bent strips at one end of each panel being cut away to leave projecting portions of less than the full depth, the straight bars on the abutting end of the next panel being notched to engage and hook around said projecting portions of the bent strips of the first panel, and all said interlocking portions being pinned together when the adjacent ends of the panels are interleaved to form a connecting joint 130

by connecting means passing through the projecting portion of said bent strip ends.

2. A combination such as defined in claim 1 in which said notches and projecting extremities are all located along the lower edges 5 of the bars and strips.

3. A combination such as defined in claim 1 in which the depth of the notches in the straight bars, and projecting portions of the 10 bent strips, are each of one half the depth of the main body of the grating.

4. A combination such as defined in claim 1 in which the straight bars are considerably longer than the bent strips and have their 15 resultant overlapping portions held together by additional clamping means.

5. As a new article of manufacture a panel of grating adapted for use as a standardized unit for built-up grating structures of any 20 desired length, which panel comprises a series of parallel bars of uniform length and depth, held together but spaced apart by intervening bent strips of the same depth and of a uniform but lesser length, the ends of 25 each of said straight bars projecting substantially at equal distances beyond the ends of a bent strip adjacent one side thereof, the projecting portions of the straight bars at one end of the panel being notched, and the 30 ends of the bent strips at the other end of the panel being partly cut away, the shape and location of said notches and of the uncutaway portions of the bent strips being similar one to another; whereby, on assembling 35 a series of such panels to form a continuous grating, the uncutaway portions of the bent strips in any one panel may be nested in the notches cut in the straight bars of the next panel abutting that end.

6. A panel of grating such as defined in 40 claim 5 in which said notches are located in the under edges of the straight bars.

7. A panel of grating such as defined in 45 claim 5 in which said notches and projecting, uncutaway portions of bent strip ends are all of one half the depth of the main body of the grating panel.

8. As a new article of manufacture a panel 50 of grating adapted for use as a standardized unit for built-up grating structures of any desired length, which panel comprises a series of parallel bars of uniform length and depth, held together but spaced apart by intervening bent strips of the same depth and of a uniform but lesser length, the ends of each 55 said straight bars and bent strips being free from permanent fastening means one to another, the unfastened portions of the straight bars at one end of the panel being notched, and the ends of the bent strips at the other end of the panel being partly cut away, the shape and location of said notches and of the 60 uncutaway portions of the bent strips being similar one to another; whereby, on assem- 65

bling a series of such panels to form a continuous grating, the uncutaway portions of the bent strips in any one panel may be nested in the notches cut in the straight bars of the next panel abutting that end.
